FEELER MECHANISM FOR LOOMS

Application filed May 14, 1929. Serial No. 362,915.

This invention relates to feeler mechanisms for looms whereby a train of mechanism is set in operation to effect replenishment of filling when that in the shuttle is substantially exhausted, and is more particularly directed to feeler mechanisms of the side slipping type.

In feeler mechanisms of the side slipping type the feeler usually enters the shuttle on each detecting beat, contacts with the filling, and when filling is substantially exhausted the feeler is given a movement in a direction longitudinally of the shuttle. This longitudinal movement of the feeler may be effected by the forward pressure upon the feeler or by means which acts on each detecting beat to impart a tendency to the feeler to side slip.

In this latter type of side slipping feeler the lateral stress upon the feeler is exerted as the lay moves forwardly and continues in action until the lay retreats, with the result that frequently the filling in the shuttle is subjected to injury and the coils of filling may become displaced so that breakage may occur. This is particularly manifest in a side slipping feeler having a number of filling engaging teeth and where the lateral stress upon the feeler is maintained during its entire forward movement.

One of the important features of the present invention consists in a side slipping feeler of light and sensitive character which is given its tendency to side slipping movement on each detecting beat and when moved forwardly by a working supply of filling a predetermined distance, the tendency for side slipping movement is relieved so that the working supply of filling is not subjected to injurious effect by the lateral stress of the feeler.

As hereinabove mentioned, the injurious effect upon the filling by a side slipping feeler is especially pronounced where the feeler has a number of filling engaging teeth, and another feature of the present invention consists of a wire feeler, the rear end of which is cut on an incline extending through the entire body of the feeler to provide a single tooth which may enter between the coils of

filling on each detecting beat and be effectively held from side slipping movement without the disadvantages of filling injury.

The invention and novel features thereof will best be made clear from the following description and the accompanying drawings of one good form thereof.

In the drawings:

Fig. 1 is a perspective view showing the feeler mechanism of the present invention and portions of the lay and shuttle box and shuttle, some of the parts being broken away;

Fig. 2 is a plan view showing the relation of parts when the feeler detects a working supply of filling in the shuttle and has been moved forwardly a predetermined amount thereby; and

Fig. 3 is a plan view showing the relation of parts when the feeler has detected substantial exhaustion of filling and partakes of its side slipping movement.

The invention as shown is intended to be associated with means for changing the loom operation upon side slipping movement of the feeler, and such operation may be replenishment of filling. The replenishing mechanism, however, is not herein shown and described because the details thereof form no part of the present invention and are now well understood in the art.

The shipper stand 1 is of usual character and has extending therefrom the arm 2 for the support of a bracket 3 which may be adjustably connected to the arm by a bolt 4 passing through a slot 5 of the arm.

The feeler stand 6 is secured to the bracket 3 by a bolt 7 which passes through a slot 8 formed in the feeler stand, whereby the feeler stand and the parts carried thereby may be properly adjusted.

The feeler stand 6 as herein shown is preferably formed of light sheet metal and has an upturned flange 9 at its rear portion provided with a slot 10 through which the feeler 11 extends. At the front of the feeler stand there is an upturned flange 12 through which the forwardly extending stem of the feeler 11 passes, and at the front end of the feeler stem there is an arm 13 which serves to limit the rearward movement of the feeler under

the call of a pull spring, as will presently appear.

The feeler 11 is formed of wire, preferably of circular cross-section, and the rear end portion of the feeler is cut on a bevel or incline through the entire body of the feeler, as indicated by the line *a*—*b*, Fig. 2, the result being that the filling feeler end of the feeler is provided with a single tooth *c* which may enter between the coils of filling on each detecting beat without injurious effect thereto.

The feeler in the present invention extends substantially at right angles to the longitudinal axis of the shuttle and consequently means are employed to move the feeler into its rearward feeling position and at the same time act laterally to return the feeler from its side slipped position in case filling has been detected as substantially exhausted.

Between the front and rear ends of the feeler the latter is provided with a projection which may be conveniently formed by bending the wire of the feeler into a lateral arm 14 for a purpose which will presently appear, and connected to the lateral arm or projection 14 is the comparatively light spring 15, one end at 16 being secured to the projection or bend 14 and the rear end of the spring at 17 is secured at the rear of the feeler stand laterally of the feeler, with the result that the spring 15 acts both in a rearward and inclined direction by its pulling stress to return the feeler to rearward position, and laterally in the slot 10 to its straight feeling position.

Pivotedly mounted at 18 at the rear of the feeler stand is a feeler displacer 19 having a bulge 20 substantially central of the displacer, and from the bulge 20 the front arm 21 of the feeler displacer inclines frontwardly away from the feeler. The terminal portion of the arm 21 has a stop 22 which is normally held in contact with a cooperating stop 23 on the feeler stand by a spring 24, one end of which is connected to the feeler displacer at 25 and the other to the feeler stand at 26, the result being that the feeler displacer will normally take position as indicated in Fig. 1.

In the present instance of the invention, the feeler displacer has an arm 27 extending slightly frontward of its pivotal mounting 18, and, as shown, the rear end of the spring 15 is connected to the arm 27, so that should the feeler displacer be moved laterally by the feeler projection 14 as the feeler is moved frontwardly, the arm 27 will swing laterally to move the rear end of the spring in a direction increasing the lateral pull stress of the spring upon the feeler.

The feeler stand 6 which as hereinbefore stated is preferably formed of sheet metal, has an eye 28 through which loosely extends a transmitter 29, the end 30 of which bears upon the side of the feeler, the construction being such that should the feeler partake of its side slipping movement the transmitter 29

will be moved to initiate replenishment of filling through a usual train of mechanism now well understood.

When the feeler is in its rearward feeling position, the projection or bend 14 of the feeler will be rearward of the bulge 20 of the feeler displacer 19, so that on frontward movement of the lay the single filling engaging tooth of the feeler will sink into the filling before the projection or bend 14 of the feeler contacts with the feeler displacer, thereby insuring that the feeler be held by the filling in the shuttle provided a working supply is present. As the feeler is moved frontwardly, the projection or bend 14 of the feeler will engage the bulge 20 of the feeler displacer and consequently impart to the feeler a tendency to side slip. Should a working supply of filling be present in the shuttle on a detecting beat, the projection or bend 14 of the feeler will be moved frontwardly past or beyond the bulge 20 and engage the frontwardly inclined arm 21 of the displacer, thereby relieving the feeler from its full side slipping tendency, which is at a maximum when the projection or bend 14 is at the peak of the bulge 20.

The release of the maximum side stress upon the feeler under the conditions above noted has the result of relieving the filling from injurious side stress by the single tooth of the feeler.

Should, however, the filling be substantially exhausted on a detecting beat, as indicated in Fig. 3, the feeler will not be moved frontwardly as far as when a working supply of filling is present in the shuttle, and the projection or bend 14 will rest substantially upon the peak of the feeler displacer, thereby imparting the maximum tendency of the feeler to side slip, and since the spring 15 is given a more lateral direction of pull upon the feeler as it side slips, such spring 15 is of less pulling strength than the spring 24 which yieldingly holds the feeler displacer in its operative position.

From the construction described it will be apparent that the single bevelled tooth of the feeler when engaged with a working supply of filling on a detecting beat, as indicated in Fig. 2, will be relieved of its maximum side stress upon the filling as the feeler moves frontwardly and carries the projection or bend 14 frontward of the bulge 20 of the feeler displacer, and such release of the side slipping tendency of the feeler will relieve the filling of any injurious effect by the single tooth of the feeler.

Should the filling be substantially exhausted on a detecting beat, however, the feeler will not be moved frontwardly sufficiently far to carry the projection or bend 14 frontward of the bulge 20 of the feeler displacer and the latter will exert its maximum side slipping tendency against the feeler to effect

lateral movement of the transmitter 29 and initiation of filling replenishment.

The lay 31 which is shown broken away is of usual character and has the shuttle box 32 in which the shuttle 33 rests when it is positioned in the box at the detecting side of the loom. The front wall 34 of the shuttle is provided with the usual opening 35 to permit entrance of the feeler to engage the filling 36 on the filling carrier 37. It is understood, of course, that the front wall of the shuttle box is likewise provided with an opening to permit the feeler to enter and detect the condition of the filling.

15 What is claimed is:

1. In a feeler mechanism for looms, the combination of a feeler stand, a side slipping feeler mounted on the feeler stand and provided with a projection between its ends, a feeler displacer pivotally mounted at the rear of the feeler stand and having a substantially central bulge for engagement by the feeler projection as the feeler is moved frontwardly to impart to the feeler a tendency to side slip, and an arm extending frontwardly from the bulge in a direction inclined away from the feeler to lessen the side slipping tendency of the feeler when it is moved frontwardly a predetermined amount.

20 2. In a feeler mechanism for looms, the combination of a feeler stand, a side slipping feeler mounted on the feeler stand and having a projection between its ends, a feeler displacer comprising an arm pivotally mounted at the rear of the feeler stand and inclined frontwardly towards the feeler to form a bulge and impart to the feeler a side slipping tendency as the feeler is moved frontwardly, and an arm extending frontwardly from the bulge away from the feeler to modify the tendency of the feeler to side slipping movement when the feeler has been moved frontwardly a predetermined amount and a spring for yieldingly holding the feeler displacer in an operative position.

25 3. In a feeler mechanism for looms, the combination of a feeler stand, a side slipping feeler mounted on the feeler stand and having a projection, a feeler displacer pivotally mounted at the rear of the feeler stand and having a bulge forward of the feeler projection when the feeler is in rearward feeling position and a release portion forward of the bulge to relieve the feeler from the full tendency to side slip when the feeler projection is moved frontwardly past the bulge, and a spring connected to the feeler displacer to maintain it yieldingly in operative position.

40 4. In a feeler mechanism for looms, the combination of a feeler stand, a side slipping feeler mounted on the feeler stand and having a projection, a feeler displacer having a bulge for engagement by the projection to effect side slipping movement of the feeler

when the filling is substantially exhausted and a part frontward of the bulge to relieve the feeler of side stress when a working supply of filling is in the shuttle on a detecting beat and the feeler projection is moved frontwardly past the bulge to thereby avoid injury to the filling.

45 5. In a feeler mechanism for looms, the combination of a feeler stand, a side slipping wire feeler having a single filling feeler tooth and a bend between its ends forming a projection, a yielding pivotally mounted feeler displacer having a bulge for engagement by the projection to exert a lateral stress upon the feeler as it is moved frontwardly and a stress relieving part frontward of the bulge to relieve the lateral stress upon the feeler when the feeler projection is moved frontwardly past the bulge by a working supply of filling in the shuttle on a detecting beat to prevent injurious effect upon the filling by the single tooth of the wire feeler.

50 6. In a feeler mechanism for looms, the combination of a feeler stand, a side slipping wire feeler mounted on the feeler stand and having its rear end cut to form a single filling feeler tooth, and means acting upon the feeler tending to cause side slipping movement thereof until the feeler is moved frontwardly a predetermined distance on a detecting beat and thereupon relieving the feeler from side slipping tendency to prevent displacement of the filling by the feeler when a working supply of filling is present in the shuttle on a detecting beat.

55 7. In a feeler mechanism for looms, the combination of a feeler stand, a side slipping wire feeler mounted on the feeler stand and having its rear end cut transversely through the wire feeler on an incline to form a single filling feeler tooth, and means exerting side stress upon the feeler until it is moved frontwardly a predetermined amount and thereupon relieving the side stress upon the feeler to prevent displacement of the filling by the feeler on a detecting beat when a working supply of filling is in the shuttle.

60 8. In a feeler mechanism for looms, the combination of a feeler stand, a side slipping feeler mounted on the feeler stand and having a projection, a pull spring connected to the feeler and at a point laterally of the feeler at the rear of the feeler stand to act in a rearwardly inclined direction upon a feeler, a feeler displacer pivotally mounted at the rear of the feeler stand and having a bulge for engagement by the feeler projection as the feeler is moved frontwardly on a detecting beat, an arm forward of the bulge inclined frontwardly away from the feeler, and a spring of greater strength than the pull spring to maintain the feeler displacer in normal operative position against the lateral stress of the pull spring as the feeler side slips.

9. In a feeler mechanism for looms, the combination of a feeler stand, a side slipping feeler mounted on the feeler stand to extend rearwardly therefrom at right angles to the lay movement and constituted as a light single wire blade having a filling feeler tooth rigid with the feeler, bearings on the feeler stand through which the wire feeler has movement towards and from the front of the loom, and a feeler displacer acting yieldingly upon the feeler to impart side slipping movement thereto until the feeler is moved forward a predetermined amount on a detecting beat and thereupon freeing the feeler from side stress to prevent displacement of the filling by the feeler.
10. In a feeler mechanism for looms, the combination of a feeler stand, a feeler mounted upon the feeler stand for movement towards and from the front of the loom and in a direction longitudinally of the shuttle, and a feeler displacer which acts yieldingly upon the feeler tending to move it longitudinally of the shuttle until the feeler has been moved forwardly a predetermined amount on a detecting beat and thereupon relieving the side stress upon the feeler to prevent displacement of the filling by the feeler as it completes its further forward movement.
15. In testimony whereof, I have signed my name to this specification.

JESSE W. SIMPSON.
